CURTAIN

Irving R. Grundstein, New York, N. Y., assignor
to Fall River Curtain Company, Inc., New
York, N. Y.

Application March 14, 1940, Serial No. 323,892

5 Claims. (Cl. 156—10)

The subject matter of this invention is a curtain for improving the dress of windows although in the broadest aspect thereof it is not limited in this respect. The dominant object of the invention however is realized in the provision of a curtain having a pair of slidably guided wings enhanced in appearance by a compensatory and serviceable valance member adjustable relative to the wings and widthwise of the latter. Other important objects, features and functional and structural aspects and advantages of the invention will appear from the following detailed description considered in the light of the accompanying drawing wherein:

15 Fig. 1 is a front elevational and partly broken view of the curtain according to my invention.

Fig. 2 is an enlarged sectional view of the valance member taken on the line 2—2 of Fig. 1.

Fig. 3 is a plan view of Fig. 1.

20 Fig. 4 is another front elevational and broken view showing the curtain according to the invention but mounted on an arcuate support.

Fig. 5 is a plan view of Fig. 4.

25 Fig. 6 is a sectional view on the line 6—6 of Fig. 4.

Fig. 7 is a perspective view of the valance member.

Fig. 8 is an enlarged sectional view on the line 8—8 of Fig. 1.

30 Fig. 9 is an enlarged sectional view on the line 9—9 of Fig. 3.

Fig. 10 is a fragmentary perspective view of the reinforced envelope or casing, and

35 Fig. 11 is an enlarged elevational and broken view of a fragmentary part of Fig. 7 bounded within the circle shown in dash and dot lines.

In the drawing, the curtain is generally denoted C and comprises the pair of wings W having the customary sockets S at their upper margins for slidably receiving a conventional supporting adjustable bar B sustained in the usual fashion above a window not shown.

40 To enhance the appearance created by the wings and to compensate for their incompleteness in width in instance for example, where the combined width of the wings is less than the width of the window, a valance member V is utilized and is sustained by the bar and draped over the intervening gap defined by the spaced wings W.

45 The interstitial valance member comprises a plurality of superimposed panels P appropriately secured to provide a pleasing cascade effect although the central panel is in two plies and in part is folded over the supporting bar B and the

wings W, to provide a U-shaped portion or bight 10 from which depends the marginal portion 11 having secured or stitched thereto the envelope or casing 12 reinforced by the insert 13 which may be of a relatively stiff buckram material.

5 More particularly however the side 14 of the envelope 12 is provided with the turned over flange 15 to define lip 16 while the upper portion of the side 17 of the envelope is likewise turned over to provide flange 18 to characterize lip 19, 10 the insert 13 being interposed between lip 19 and the bight or lip 20 defined by the diverging sides 14 and 17 of the tube 12 to prevent widthwise displacement of the insert. Thereafter the end flanges 21 of the side 17 are folded inwardly 15 against the ends of the insert to prevent longitudinal displacement thereof relative to the woven or interstitial tube or envelope 12. Subsequently the end flanges 21' of side 14 are folded inwardly and over the depending flange 15 after 20 which the line of stitching 22 is passed through the upper margins of the woven insert 13, juxtaposed flanges 15 and 18, the flanges 21 and 21'; the two ply flange 24 of the central panel and the single ply flange 24' of the other panels 25 and the sides 14 and 17 in the matter of securing together lips or beads 16 and 19 and the lip 23 defined by the turned over flange 24 of the depending marginal portion 11 of the central panel P of the valance.

30 By the present arrangement the reinforcing insert is prevented from longitudinal and widthwise slippage and is appropriately concealed in the envelope by the secured closure end flanges 21. Hence it is apparent that where the upper part of the valance is draped over the wings of the curtain and supporting bar, the valance is prevented from accidentally slipping off the bar B since the reinforced lip 19 automatically abuts or interlocks with the lower part 25 of the bar B as shown in Fig. 2 or abuts walls 26 of the sockets of the wings, crimping these walls toward and against the lower portion 25 of the sustaining bar B. Normally the reinforcing envelope is held in an inclined or biased relation as illustrated in 35 Figs. 2 and 8 and hence cooperates to hook under the bar to retain the valance on the bar or on the wings, the envelope in fact being rendered relatively heavy by the relatively stiff interstitial insert.

40 In the form according to Figs. 4 and 6 the wings and valance member are mounted on a tubular and arc shaped bar, and slippage of the valance member from the bar and wings is prevented as described in connection with the form 45 50 55

illustrated in Figs. 1-5 in that the biased and reinforced envelope cooperates with the bar and the wings on the bar to characterize an interlocking action, thus precluding accidental slippage of the valance member completely off the bar.

With the present invention the overall width of the wings may be less than the complete width of the window and the slideable and adjustable valance member may be conveniently mounted over the wings and bar to enhance and complement the appearance of the wings as is well appreciated.

As many changes can be made in the above construction and many widely different species of structural embodiments of the invention can be devised without departing from the scope thereof, it is intended that all matter herein described in the specification and illustrated in the accompanying drawing shall be interpreted as illustrative and not in a limiting sense.

I claim:

1. A valance member adapted to be draped over a support and having a casing adapted to be arranged below and in back of said support and including a bead and reinforcing means in said casing to strengthen said bead and adapted to be disposed in biased relation relative to said support to dispose said bead underneath said support for abutting the latter to resist accidental removal of said member from said support.

2. A valance member adapted to be draped over a support and slideable relative thereto and having relatively stiff reinforcing means adapted to be disposed in biased relation below and in back of said support and having marginal means for abutting said support to resist accidental removal of said member from said support.

3. A valance member adapted to be draped over a support and having a swingable casing adapted to be disposed at the rear of and below said support and comprising a beaded portion and a bight portion, and an insert interposed between said beaded portion and said bight portion to reinforce both of the latter, said beaded portion adapted to be arranged in a biased relation relative to said support and having a marginal portion cooperating to abut said support to resist accidental removal of said member from said support.

4. A valance member adapted to be draped over a support and having a swingable casing comprising a beaded portion and a bight portion, and an interstitial and relatively heavy insert interposed between said beaded portion and said bight portion to reinforce both of the latter and for disposing said casing in a biased relation relative to said support, said beaded portion cooperating to abut said support to resist accidental removal of said member from said support.

5. A valance member adapted to be draped over a support and having a casing comprising juxtaposed beaded means secured to said member and including a bight portion, and a relatively stiff insert interposed between one of said beaded means and said bight portion to reinforce both of the latter and said casing, said casing having end closure means to resist longitudinal displacement of said insert, said casing adapted to be disposed in a biased relation relative to said support and said reinforced beaded means adapted to abut an underneath portion of said support to preclude accidental removal of said member from said support.

IRVING R. GRUNDSTEIN.
